UNITED STATES PATENT OFFICE.

GUSTAVUS RICHTER, OF MILDENAU, BOHEMIA, AUSTRIA.

RESERVOIR FOR PETROLEUM.

SPECIFICATION forming part of Letters Patent No. 244,078, dated July 12, 1881.

Application filed March 29, 1881. (No model.) Patented in Belgium and in France August 23, 1880.

To all whom it may concern:

Be it known that I, GUSTAVUS RICHTER, a subject of the Emperor of Austria, residing at Mildenau, in the Kingdom of Bohemia, Empire of Austria, have invented a new and useful Reservoir for Petroleum and other Oil, &c., (for which I have obtained Letters Patent in Belgium, No. 52,379, and in France, No. 138,382, both dated August 23, 1880,) of which the following is a specification.

My invention relates to improvements in oil-reservoirs in which the material or fluid is pumped up and runs into a vessel put on the cover of the reservoir; and the objects of my improvements are, first, to make the overflowing material run back directly to the reservoir, and, second, to provide a mechanism for keeping such reservoir under lock and key. I attain these objects by the mechanism illustrated in the accompanying drawings, in which—

Figure 1 is a vertical section of a reservoir with my improvement attached. Fig. 2 is a detailed section of the collecting-funnel. Fig. 3 is a horizontal section through the cock, at line 22, Fig. 2. Fig. 4 is a top view of the reservoir. Fig. 5 is a modification of the funnel provided with measuring apparatus. Fig. 6 is a section of the measuring apparatus, and Fig. 7 is a side elevation of the same.

Similar letters refer to similar parts in all the figures.

The tank A is provided with a pump-cylinder, X, which is in connection with the discharge-pipe g. In said cylinder a piston-rod, 35 x, and piston x' reciprocate, said rod being provided with a handle, X'. Said handle has a screw-threaded downward extension, which may be made to engage with similar internal threads in the top of tank A, so as to lock the 40 piston. When the piston is moved up and down in the usual way the liquid is forced from tank A into and through pipe g. As the air within measuring-tube h would naturally resist the inflow of liquid through openings m, I provide said tube, as shown in Fig. 4, with an air-outlet tube, h'. This tube is provided with a stopper, h², which is suspended therefrom by a cord or chain. When the tank or reservoir 45 has been sufficiently supplied with liquid this stopper is inserted in the mouth of the outlet-

tube for the purpose of excluding dust. The pressure of air while liquid is flowing into the tank will often suffice to eject this stopper and open the outlet; or the stopper may be withdrawn by hand. The curved upper end of this pipe g is bent just over the center of the tank and provided with a cock, l, or with the measuring apparatus h, in which the discharge-pipe g goes up nearly to the top of the apparatus h, Fig. 6, and is surrounded by the larger pipe 55 i. This outer pipe, i, has small openings m at its lower end, through which the oil or fluid runs into the glass tube or chamber h, where the scale k, Fig. 7, shows the quantity. The cock l serves to discharge the contents of the 60 glass tube h into a vessel placed under it.

The top D of the reservoir has on its inner side a funnel-shaped chamber, B, attached, provided with a perforated plate, f, and a cock, d, at its lower end. The perforated plate f 70 serves to retain dirt and dust which may be mixed with the oil or fluid. This chamber B is closed by a cover, a, provided with a bracket, b, having an opening, which, when brought in line with the handle of the pump X, can easily 75 be locked to the same. The stem e of the cock d is connected by solder or otherwise to a suitable projection, r, on the under side of this cover a, by which arrangement the turning of the cover a will open or shut the cock d, and 80 thereby close the reservoir when desired.

The cover a is provided with a recess, a', capable of passing over the head of a pin, c, fixed into the reservoir-cover D. Another pin with a large head, c', is likewise secured to this 85 cover D. When the cover a is put over the collecting-funnel B it must be pushed first under the head of the pin c' in such a manner that the recess a' passes over or around the head of the other pin, c. In this position the 90 cock d will be open, and any overflow of oil or liquid will pass into the funnel-chamber B, through the cock d, back into the reservoir A. When the cover a is turned till the bracket b comes into line with the handle of the pump, 95 the same can readily be locked to said handle, and by this turning of the cover the cock d will be shut, closing thereby the reservoir.

The modification of the cover a shown in Fig. 5 only consists in an indentation or recess 100

in the central part of said cover, and is more particularly used for tanks provided with the measuring apparatus.

I am aware that prior to my invention reservoirs for petroleum, oil, and other fluids have been made with a pumping mechanism operating in conjunction with a measuring apparatus, and I therefore do not claim such a combination, broadly; but

10 What I claim as my invention, and desire to secure by Letters Patent, is—

1. The combination, in a reservoir for petroleum, oil, or other fluid, of a collecting-funnel, B, having a perforated plate, f, with the cock 15 d and the cover a, arranged to operate substantially in the manner and for the purpose described.

2. In a reservoir for petroleum, oil, or other fluid, the combination of the collecting-funnel B with the perforated cover a, having a recess, 20 a', the bracket b, and the two pins c and c', substantially as and for the purpose set forth.

3. The combination of funnel B, cover a, cock d, stem e, and bracket b, having an opening in its outer end, with the handle X' of a 25 pump piston-rod, said parts being so arranged that the said bracket and handle can be conveniently tied together or otherwise locked to each other, for the purpose set forth.

GUSTAVUS RICHTER.
